UNITED STATES PATENT OFFICE.

GEORGE L. FOGLER, OF PITTSBURGH, PENNSYLVANIA.

GAS-BURNING FURNACE.

1,045,829.

Specification of Letters Patent.

Patented Dec. 3, 1912.

Application filed October 17, 1911. Serial No. 655,221.

To all whom it may concern:

Be it known that I, GEORGE L. FOGLER, a resident of Pittsburgh, in the county of Allegheny and State of Pennsylvania, have 5 invented a new and useful Improvement in Gas-Burning Furnaces, of which the following is a specification.

This invention relates to gas burners for heating furnaces, such as are used for heating 10 dwellings or boilers for power purposes.

The object of the invention is to provide an improved construction of burner in which the supplies of gas and air are thoroughly intermingled, and brought into such close 15 mutual contact that complete combustion will result and in which the mixture of gas and air is burned in a combustion chamber tightly sealed and having no other air inlet than from the burner itself, whereby a more 20 uniform and perfect draft, automatically controlled by the supply of gas, is obtained, and wherein the heated products of combustion yield for heating purposes all or a very large proportion of the heat units resulting 25 from the combustion.

In the accompanying drawing Figure 1 is a vertical cross sectional view of my invention as applied to a hot air heating furnace for household heating purposes; Fig. 2 is a 30 horizontal cross section on the line 2—2, Fig. 1; Fig. 3 is an enlarged vertical cross sectional view through the burner; Fig. 4 is a horizontal cross sectional view on the line 4—4, Fig. 3 looking in the direction of 35 the arrow; Fig. 5 is a perspective view of the mixing chamber, and Fig. 6 is a cross sectional view through the preliminary mixing chamber on the line 6—6, Fig. 3.

The gas supply pipe is indicated at 1. 40 This may be connected to a gas main or any other suitable source of artificial or natural gas. This supply pipe is provided with a suitable regulating cut-off valve 2. The supply pipe communicates with a tapered 45 jet or nozzle 3 projecting into a preliminary mixing chamber 4. The side of the preliminary mixing chamber 4, around the jet 3, is provided with air inlet openings 5 which are covered by a suitable regulating 50 sleeve 6 having openings 7 therein, this sleeve being preferably so mounted between shoulders 7^a on the chamber as to turn about the preliminary mixing chamber and regulate the admission of air into the same. The 55 gas entering through the inlet 3 draws in with it a certain quantity of air through the

openings 5, not sufficient however for perfect combustion. This gas and air by reason of the action of the jet 3 is well mixed in the chamber 4 and then passes to its opposite end where it streams out into a supply pipe 8 which at its other end is provided with a tapered nozzle 9 projecting into a casing member 10 forming the final mixing chamber. As shown in Figs. 1 and 3, the 60 nozzle 9 is tapered, with its smaller end projecting forwardly, and passes through the lower end of the mixing chamber and also through a plate 12, preferably brazed or otherwise fastened to the nozzle 9, and which 65 is arranged forwardly of the base of the mixing chamber and is provided with a plurality of small perforations 13 surrounding the nozzle 9. In the base of the mixing chamber 10 and in rear of the plate 12 are 70 a series of notches or apertures 14 for the free admission of air into the mixing chamber, and it is intended that the size of the apertures 14 and of the orifice 11 shall be 75 such that the mixed gas and air entering 80 through the nozzle 9 will suck or draw in, through the apertures 14, just enough additional air to form the proper mixture for perfect and complete combustion. The nozzle 9 is provided with a flange 9^a to which 85 is brazed or otherwise fastened the lower end of the mixing chamber 10 to support the latter, and, as shown in Fig. 4, is oblong in cross section. In other words, in the form shown, it is longer in one horizontal dimension than in the other dimension, and this 90 is true throughout its longitudinal extent. This arrangement causes the entering fuel supply or mixture of gas and air to be brought into close and intimate contact and 95 in passing through the restricted orifice in a thin flat stream, is thoroughly mixed in such a manner as to increase the combustion thereof.

The mixing chamber 10 leads directly, by 100 means of its orifice 11, into a combustion chamber 15 which at its base 16 is hermetically sealed around the mixing chamber 10 in such a manner that no air or gas may be admitted to the combustion chamber except 105 as it enters through the mixing chamber 10. The mixing chamber 10 is oblong in cross section and tapers from its base 17 to its orifice 11 in somewhat the same manner as the nozzle 9, as shown in Fig. 4. Forwardly 110 of the mixing chamber 10 and supported by brackets 18 attached to the sides of the com-

5 combustion chamber 15 is a hollow baffle cone 19 which is arranged with its open or concave side toward the entering mixing chamber 10. This cone, in the form shown, is provided with a plurality of small perforations 19a. The entering gas and air in its thoroughly mixed condition is directed against the cone and by being caused to pass through the perforations and around the circumference thereof, fills the full extent of the combustion chamber 15 with burning gas and flame, thus producing complete combustion of all gas admitted to the chamber.

10 In the drawings my invention is shown as applied to what is known as a "hall heating furnace". In this form of the invention, the combustion chamber 15 forms the beginning of a system of flues and chambers through which the hot gases and products of combustion pass to the chimney or stack. The flues and chambers are all contained within an outer hot air collecting casing 20, at the bottom of which, as at 21, is supported an annular hollow ring or casing 22, which is formed of inner and outer cylinders 23, bottom plate 24 and top plate 25. In the hollow ring are a number of vertical radially arranged dividing walls 26 which break up the ring into a plurality of chambers 15, 27, 28 etc. The combustion chamber 15 into which the mixing chamber leads through an aperture in its bottom, constitutes the first chamber in the lower casing 22. In the upper part of the furnace is a second hollow ring or casing 29, similar in construction to the lower one just described, and supported from the outer collecting casing 20 by angle irons or plates 30. This ring, like the lower one, is broken up into a number of chambers 31, 32 by vertical radially arranged dividing walls 33. Connecting the various chambers of the upper and lower rings are a plurality of vertical flues 34 with openings at each end thereof leading into the chambers. These flues and the dividing walls in the upper and lower rings are so arranged that the hot gases produced in the combustion chamber 15 will pass from the first or combustion chamber 15 into the first vertical flue and upwardly into the first chamber in the upper ring. This chamber has a communication with the second or adjacent vertical flue and the hot gases therefore pass into the second chamber in the lower hollow ring. They thence pass from the second chamber into the third vertical flue and upwardly into the upper hollow ring. In this manner, by providing an uneven number of vertical flues, the gases are caused to pass up and down from chamber to chamber through the flues in a zig-zag course ending finally in the last chamber 32 in the upper ring, from whence they pass outwardly through flue 35 to the chimney or stack.

15 The outer casing 20 has a converging top

36 which is provided with an outstanding flange 37 which preferably is attached to the underside of the floor of a dwelling by slips or clamps 38. The space around the flues and in the center of the collecting casing 20 is in communication with the atmosphere at its bottom through an opening 39 through the center of the lower ring. At its top the space in the center of the casing 20 communicates through the opening 40 with a register or other convenient regulating means in the floor, as is usual in hot air furnaces.

40 In the lower portion of the collecting chamber 20 an upwardly and inwardly inclined baffle plate or ring 41 is provided, extending around the inner circumference of the chamber 20 and supported above the space 42 around the lower ring by clips or irons 43 riveted or otherwise attached to the baffle 41 and ring. This baffle plate deflects such air as enters the collecting chamber 20 around the exterior of the lower ring toward the center of the chamber and into contact with the several vertical flues 34. The combustion chamber 15 is provided with a side door 44 and a door 45 is also placed in the outer collecting casing 20 directly opposite the door 44. These doors are intended to give access to the chamber 15 for cleaning purposes or for making repairs and lighting the gas. The door 44 is so constructed, however, that when closed it hermetically closes its aperture and precludes the admission of air at this point. The walls and joints of the chamber 15 and, in fact, all of the chambers and flues in the system are tightly riveted together so that a hermetical seal is provided at all points. For this reason the construction is such that the only inlet to the system of flues and chambers is into the chamber 15 through the orifice 11 of the mixing chamber 10. The only outlet from the system of flues and chambers is from the last upper chamber 32 through the flue 35 to the stack. Since free access of air to the chamber 15 and flues is prohibited it is apparent that there will be no draft therethrough. The entering gas and air, coming into the chamber 15 from a comparatively small feeding orifice are caused to flow at considerably reduced speed when they pass through the chamber 15 and subsequent flues because of the much greater relative size thereof. Consequently, it takes some time for the heated products of combustion to travel clear through the system and during all this time they steadily yield up their stored heat units to the surrounding air in collecting casing 20. In fact, with my improved system, it is found that while the chamber 15 and first flue 34 will be red hot the outgoing flue 35 will be very nearly cold.

45 As shown, my invention is applied to a hot air heating furnace. It is apparent, 50

however, that it may be equally well applied to heating plants which utilize either hot water or steam as the circulating medium. In such cases the hot water or steam would be arranged to circulate around or through the hollow rings and flues, and the hot water or steam thus produced would circulate through a proper system of pipes to the various points in the house where radiators

10 are desired. My invention may also be adapted for heating water for forming steam for power purposes by being connected to any ordinary form of power boiler.

15 The operation of the improved furnace will be obvious from the foregoing description and the accompanying drawings. The gas supply enters through the pipe 1 and is mixed in the preliminary mixing chamber 4 with a certain quantity of air which is 20 drawn in by the action of the jet or nozzle 3 through the openings 5. This preliminary mixture passes out through the oblong tapering nozzle 9 where it is more closely intermingled and sucks in a second supply 25 of air through the apertures 14 and perforations 13 in the plate 12. These small perforations cause the formation of fine jets or streams of air which attack the incoming 30 preliminary mixture and break it up more finely, thus accomplishing a second mixture and a more complete intermingling of the fuel supply. The tapered and oblong arrangement of the mixing chamber 10 then causes the gas to pass forwardly and leave 35 the mixing chamber 10 in a thin fluid stream which is introduced directly into the combustion chamber and thrown or forced against the perforated cone 19. Here it is partially thrown back and around the cone, 40 some of the mixture passing through the perforations therein and, as a consequence, the combustion chamber, which in reality is the first chamber in the lower ring, the first vertical flue and the first chamber in 45 the upper ring are completely filled with a mass of burning fuel. All the products of combustion pass up and down through the several flues and in this manner give up their stored heat units to the air passing 50 through the center of the casing, and thence pass outwardly through the final flue to the stack. The air passing up through the collecting casing 20 and around the system of flues and rings or casings becomes heated to 55 a degree depending upon the amount of fuel supplied to my improved burner and passes out through the opening 40 to the upper room, or if so desired, to a flue for conducting the same to a more distant point.

60 What I claim is:—

1. In a gas furnace, the combination of a sealed casing forming a combustion chamber and provided with an outlet for waste gases, a casing forming a mixing chamber 65 and opening into the combustion chamber, a

perforated plate in said mixing chamber, said mixing chamber casing being formed to permit free supply of air to the perforations of said plate, a nozzle projecting beyond the perforated plate and into the mixing chamber, a gas supply connection to said nozzle, and a flange on said nozzle connected to and supporting said mixing chamber casing. 70

2. In a gas furnace, the combination of a sealed casing forming a combustion chamber and provided with an outlet flue for waste gases, a casing forming a mixing chamber sealed into the base of the combustion chamber and having an oblong mouth 75 opening thereinto, a perforated plate in the base of the mixing chamber, said mixing chamber casing being formed with lateral openings to permit free supply of air to the perforations of said plate, a nozzle having an oblong mouth projecting beyond the perforated plate and into the mixing chamber, 80 and a gas supply connection to said nozzle, said connection being provided with lateral openings for admitting a supply of air 85 thereinto. 90

3. In a gas furnace, the combination of a sealed casing forming a combustion chamber and having an outlet flue, a perforated baffle member supported in said flue, a 95 tapered casing forming a mixing chamber and having its smaller end projecting into the combustion chamber and sealed thereto, the mixing chamber casing being formed with air inlets at its base, a tapered nozzle projecting into the mixing chamber, and a fuel supply connection to said nozzle. 100

4. In a gas furnace, the combination with a casing forming a combustion chamber, of a tapered oblong casing forming a mixing 105 chamber and opening and sealed into the base of the combustion chamber, said mixing chamber having air inlets to its base, a perforated transverse plate supported in the mixing chamber in advance of said air inlets, a tapered nozzle projecting through 110 said plate and opening into the mixing chamber, a fuel supply connection to said nozzle including a preliminary mixing chamber, and means for supplying air and 115 fuel to said preliminary mixing chamber.

5. In a gas furnace, the combination of a casing forming a combustion chamber and having a flue, a perforated baffle plate therein, a tapered casing forming a mixing 120 chamber sealed in and projecting into the combustion chamber, the mouth of the mixing chamber being aligned with said baffle plate, a perforated plate in the base of the mixing chamber, a tapered nozzle oblong 125 in cross section projecting through the perforated plate and into the mixing chamber, and a gas supply connection to said nozzle.

6. In a gas furnace, the combination of a casing forming a combustion chamber and 130

4
having a flue, a baffle plate supported in said flue and comprising an open-ended perforated cone, a tapered casing forming a mixing chamber leading into the combustion chamber, a perforated plate in the base of the mixing chamber, a tapered nozzle oblong in cross section projecting through the perforated plate and into the mixing chamber, the open end of said cone facing said nozzle, a preliminary mixing chamber hav-

ing means for supplying gas and air thereto, and a connection between said preliminary mixing chamber and said nozzle.

In testimony whereof, I have hereunto set my hand.

G. L. FOGLER.
